TOBACCO ASH RECEPTACLE

Nels H. Nelson, West Okoboji, Rte. 1, Milford, Iowa

Filed Nov. 18, 1957, Ser. No. 697,154

5 Claims. (Cl. 220—1)

This invention relates to tobacco ash receptacles and more particularly to a container used in connection with and to the top of an instrument panel of automotive vehicles such as automobiles, trucks, airplanes, trains and like.

The use of ash receptacles on the instrument panels of automobiles is now common. However, such vehicle ash receptacles are costly to manufacture and require the user to snuff out the cigar, cigarette or like on a grid in the top of the receptacle prior to placing the cigarette or cigar butt in the receptacle. This latter requirement is not only unsanitary and inconvenient, but in the case of the driver of the vehicle it is dangerous, due to the fact that he must, at least momentarily, take his eyes from the roadway, observe the operation, and use one hand for grinding out the ignited tobacco.

Therefore, the principal object of my invention is to provide a small, compact tobacco ash receptacle that automatically extinguishes the lighted cigar or cigarette.

A further object of this invention is to provide an ash receptacle that has a yieldable odor and/or smoke baffle that is free of spring means.

A still further object of this invention is to provide a smokestand or like tobacco ash receptacle that is easily kept in a clean and sanitary condition.

A still further object of my invention is to provide a smokestand receptacle that is economical in manufacture, refined in appearance, and durable in use.

These and other objects will be apparent to those skilled in the art.

My invention consists in the construction, arrangement, and combination of the various parts of the device, whereby the objects contemplated are attained as herein-after more fully set forth, pointed out in my claims, and illustrated in the accompanying drawings, in which:

Fig. 1 is a side sectional view of my device supported in the instrument compartment of an automotive vehicle,

Fig. 2 is a side view, partially in section, of the baffle arrangement of the device and more fully illustrates its construction,

Fig. 3 is a cross sectional view of my ash receptacle taken on line 3—3 of Fig. 1, and

Fig. 4 is a cross sectional view of my device taken on line 4—4 of Fig. 1.

Although any ash receptacle construction may be used in smokestands, desk ash receptacles and like, I show it associated with the instrument panel unit of an automotive vehicle. I have used the numeral 10 to designate the top horizontal portion of an instrument panel unit. In this top 10, I form a circular hole 11. The marginal edge portion of the top 10 is depressed as shown in Fig. 1. The numeral 12 designates the base hopper top of my ash receptacle having its wall 13 extending downwardly and inwardly terminating into a downwardly extending neck portion 14, as shown in Fig. 1. The numeral 15 designates a jar detachably threaded onto the base hopper top and loosely embracing the neck portion 14. The

2

numeral 16 designates a stop ring portion on the periphery of the base hopper top portion and above the jar 15. The circular hole 11 is of a diameter slightly greater than that of the diameter of the jar 15. The stop ring 16 is of a diameter greater than that of the diameter of the hole 11. By this construction my device is detachably lowered downwardly through the hole 11 until it is stopped by the stop ring 16. The stop ring engages the top of the instrument panel top 10, thus supporting the entire ash receptacle unit. By the panel top being depressed in the area adjacent the hole 11, the ash receptacle will be substantially flush with the top plane of the panel top, as shown in Fig. 1. The numeral 17 designates a cigarette holding rack on the top of the base hopper top. This rack also serves as a handle means for facilitating the manual lifting of the ash receptacle unit from the hole 11 or placing the ash receptacle into the hole 11. The numeral 19 designates an inverted cone baffle member embracing and secured to the outer lower end area of the neck portion. The top plane of the baffle is substantially below the bottom plane of the base hopper top portion, as shown in Fig. 1, to provide an odor and/or smoke trap area 20. The numeral 21 designates radial slit passageways in the baffle cone 19 near its center, as shown in Fig. 3. These slits terminate in an enlarged hole opening at their outer ends. The numeral 25 designates a cone baffle. The top of this baffle 25 is flexibly connected to the inverted baffle cone 19 by a chain linkage 26 or like secured to the top apex of the cone baffle 30 and the cone baffle 19, as shown in Fig. 2 and Fig. 1. By this arrangement of parts only one side top of the cone baffle will be in a vertical plane below the opening of the neck portion. Normally the cone baffle 25 will be held against swinging movement by gravity. Its balance, however, is delicate and when a cigarette butt or like is dropped to pass downwardly through the neck opening, the cigarette will strike the side of the cone baffle and swing the cone baffle laterally, as shown by broken lines in Fig. 1, thereby permitting the cigarette butt to fall into the bottom area of the container 15. After the cigarette butt has passed the cone baffle 25, the cone baffle 25 will by force of gravity return to a normal position where one of its sides will extend in space relationship completely under the neck opening. With the cone baffle back into normal position, any smoke or odor from the cigarette butt will be deflected away from the open neck and back up and into the trap area 20. Any downward movement of the smoke or like will pass from the area 20 through the slots 21, thence be baffled by the cone 25 toward the bottom area of the container. By such an arrangement of parts, the lit cigarette butt may be dropped into the container and will automatically be extinguished. The diameter of the cone baffle 25 is more than twice the diameter of the neck opening and therefore only one side portion is below the neck opening and one side area is completely outside the vertical plane of the neck opening.

Herebefore smokestands have had baffles, but either the baffle was rigid or spring supported directly below the neck opening. Such structures readily become distorted. By suspending my baffle 25 flexibly to the neck portion and offset relative to the neck opening, I have provided a tobacco ash receptacle that is most durable, sanitary and capable of receiving any size object that will pass through the neck opening. Due to the delicately balanced cone baffle 25, it is easily pushed to one side.

Some changes may be made in the construction and arrangement of my Tobacco Ash Receptacle without departing from the real spirit and purpose of my invention, and it is my intention to cover by my claims, any modi-

fied forms of structure or use of mechanical equivalents which may be reasonably included within their scope.

I claim:

1. In an ash receptacle, a container, a hopper top having a single vertical neck opening communicating with the inside of said hopper top, and a cone baffle operatively flexibly suspended from said hopper top and offset relative to the vertical plane of the vertical neck opening of said hopper top.

2. In an ash receptacle, a container, a hopper top having a single vertical neck opening communicating with the inside of said hopper top, a cone baffle operatively flexibly suspended from said hopper top and offset relative to the vertical plane of the vertical neck opening of said hopper top, and an inverted cone baffle in a plane above the plane of said first cone baffle.

3. In an ash receptacle, a container, a hopper top having a single vertical neck opening communicating with the inside of said hopper top, a cone baffle operatively flexibly suspended from said hopper top and offset relative to the vertical plane of the vertical neck opening of said hopper top, and an inverted cone baffle in a plane above the plane of said first cone baffle; said inverted cone baffle having passageways.

4. In an ash receptacle, a container, a hopper top having a single vertical neck opening communicating with

the inside of said hopper top, a cone baffle operatively flexibly suspended from said hopper top and offset relative to the vertical plane of the vertical neck opening of said hopper top, and an inverted cone baffle in a plane above the plane of said first cone baffle; said inverted cone baffle having radially extending slit passageways.

5. In an ash receptacle, a container, a hopper top having a single vertical hole communicating with the inside of said container, and a cone baffle operatively flexibly suspended from said hopper top, having a diameter substantially twice as great as that of the diameter of the vertical hole of said hopper top and having one complete side area extending outside of the vertical plane of the hole of said hopper top.
